PLUMB BOB

Lew Suverkrop, Bakersfield, Calif.

Application December 17, 1954, Serial No. 33,595

Term of patent 14 years

(Cl. D52—1)

Fig. 1 is a side elevation of a plumb bob embodying my new design.

Fig. 2 is a plan view of the plumb bob shown in Fig. 1.

Fig. 3 is another side elevation of the plumb bob shown in Fig. 1, shown partly in section along the line A—A of Fig. 2.

The essential feature of the design resides in the cap shown in full lines.

I claim:

The ornamental design for a plumb bob, as shown and described.
